FRANZ SCHIMMEL, OF TOURNON, FRANCE.

PROCESS AND DEVICE FOR RECORDING SET-UP LINES ON MACHINES FOR CASTING
AND SETTING MOVABLE TYPE.

Application filed May 15, 1923. Serial No. 639,177.

To all whom it may concern:

Be it known that I, FRANZ SCHIMMEL, citizen of the Republic of Czechoslovakia, residing at Tournon, Ardeche, France, engineer, have invented Processes and Devices for Recording Set-Up Lines on Machines for Casting and Setting Movable Type, of which the following is a full, clear, and exact description.

10 In machines for casting and setting movable type, it is necessary to know what must be the thickness of the spaces before the type and spaces composing a line are cast. It is therefore indispensable, before casting, to compose the line entirely, to add the width of the letters and to determine the width of the spaces, according to the number of spaces contained in this line and according to the importance of the margin 15 to be filled.

For obtaining this result on certain machines, the composition is recorded on a strip of special paper by perforating it and indicating at the end of each line by separate perforations the value of the spaces, which is mechanically determined by an apparatus adding the values of the letters.

This strip of paper can only be used for a single composition and the amount of paper used daily is considerable; moreover, the casting of the composition can only be effected by beginning with the end of the article. In fact, this end must first be presented in the casting machine, so that, at 35 each line, the mould may be adjustably opened to an extent suitable to the width of the spaces of the line under consideration. This method has for disadvantage that the correction of the composition can only be effected after the composition has been recorded on the strip and after the article has been entirely cast in the casting machine, thus resulting in a delay prejudicious in 40 urgent cases.

45 Moreover, for the same reason, as the paper strip cannot directly pass from the keyboard to the casting machine, a person is necessary for recording the composition on the paper strip and another for supervising the casting machine.

The present invention is adapted to remedy these inconveniences. It allows of recording the lines without use of paper strips, consequently in an economical manner, and of effecting the recording and casting on the same machine and by the same person, so that supplementary expenses are done away with and a saving of labour is realized.

Besides, the lines being cast in proportion as they are recorded, that is to say with the beginning of the article, it is possible in urgent cases to begin the correction before the article is entirely composed.

The device allowing to obtain these advantages essentially comprises a drum internally carrying series of pawls to which a determined position may be given by means of the keyboard. By depressing a key in the keyboard of the machine, two of these 55 pawls are put in operative position. The drum immediately rotates to the extent of one division and presents a second series of pawls in front of the keyboard; the depression of another key acts on two corresponding pawls of the second series; the drum moves round and so on until an entire line is thus recorded. The end of the line is then indicated by depressing a special key and the second line is recorded. The successive rotary movements of the drum bring the first pawls placed in operative position in front of a series of control levers connected to the casting mechanism and by 60 acting on the said levers, determine the stoppage of the matrix with the required letter in front of the mould, the casting and the discharge of the type. From this moment, upon each depression of a key of the keyboard, the corresponding letter is 65 recorded on the drum and at the same time a letter of the first line, previously recorded, is cast and pushed in the composing-stick. The pawl lift by the key indicating the end of the line then determines the introduction of the cast and set up line in the galley. In this manner, the casting of the type is effected in proportion to the depressions of keys, the types of a line being cast during the time the next line is recorded. 70

In the above mentioned operations, the keyboard does not control the advance of the drum directly, but indirectly, through the medium of a mechanism for counting the thicknesses of the letters. The keyboard first acts on the counter which records the width of the letter depressed on the keyboard and it is only at the beginning of its movement that this counter acts in its turn on the mechanism causing the drum to rotate.

At each depression of a key, the keyboard acts on the counter which moves at the same time a visible index indicating the length of the line recorded. Near the end of the line, this index acts on an alarm bell so that the operator may terminate his line.

The thickness of the spaces for each recorded line is determined by the counter by means of a dividing device combined with the same. Each space is counted on the counter for its minimum thickness. At the end of the recorded line, the remaining margin to be spaced is automatically divided by this dividing device according to the number of the spaces and the result is transmitted to the adjusting device of the mould for the spaces. Thus the mould receives in addition to its minimum opening, a supplementary opening movement corresponding to the result of the division of the margin by the number of spaces, this giving to each space the exact width and allowing to obtain exactly justified lines.

This process and devices are applicable to any machine for casting and setting and they are described hereafter by way of example as applied to a machine called "La Rototype" forming the subject-matter of United States Patents Nos. 1,042,285 and 1,195,742.

The invention is illustrated, but by way of example only, in the accompanying drawing in which:

Fig. 1 is a front view of a "Rototype" machine provided with the new devices for recording and justification.

Fig. 2 is a partial view of the left-hand side of the machine, with a diagrammatic view of the space recording device.

Fig. 3 is a partial view of the right-hand side of the machine.

Fig. 4 is a detail view of the recording pawls.

Fig. 5 is a vertical section of the keyboard, the dividing device being shown in side view.

Fig. 6 shows the keyboard, counter, dividing device, galley and recording drum.

Fig. 7 illustrates details of the clutch producing the rotary movement of the drum.

Fig. 8 is a plan view of the counter.

Fig. 9 shows the details of the device for stopping the cylinder of the counter through the medium of the keyboard.

Fig. 10 is a side view of the intermediate levers between the keyboard and the counter.

Fig. 11 illustrates details of the device for recording the values of the spaces.

Figs. 12 to 19 are detail views.

As illustrated in the drawing, on a "Rototype" machine 1 is secured a support 2, carrying several guide rollers 3 on which bears a drum 4. This drum 4 internally carries a number of pawls 5, Figs. 3, 4 and 6, separated from each other by washers 6, Figs. 3 and 4, and regularly distributed on the entire inner circumference in series is equal to the maximum number of letters that the longest line composed by the machine can contain and the number of pawls in each series is determined by the number of the combinations necessary for obtaining the 120 positions of the matrices in front of the mould giving 120 letters. In the example of the drawing, the drum carries 220 series each of twenty-seven pawls.

The pawls 5 and washers 6 are threaded on axes 7 secured between the side walls of the drum 4 by screws 8 (Fig. 3), the heads of which projecting outside serve as driving means. These screws replace a toothed crown or any other driving means for determining the rotary movement of the drum on its guide rollers 3. The pawls 5 can rotate about the axes 7 but their movement is limited by a second axis 9 (Fig. 4) carried by the side walls of the drums so as to give to the pawls 5 two determined positions: one, I, position of rest, in which the pawls do not extend beyond the inner edge of the two crowns forming the drum, and the other, II, operative position, given by the depression of a key in the keyboard and in which the points of the pawls extend beyond the edge to a certain extent and can act on the levers 62 and 63 for inaugurating the casting, Fig. 6. In order that a pawl 5 may keep the position given to it, these pawls are each provided with a piston 5^a, pushed by a spring 5^b against the axis 7 which is provided throughout its length with two grooves 7^a and 7^b in which the piston 5^a can fit.

The keyboard is that described in the United States Patent No. 1,195,742 with the difference that it is secured through a support 10, Fig. 2, on the front of the machine instead of being arranged at its right hand side. By pressing on a key, a transverse bar 11 of the keyboard (Fig. 5) is lifted and moved forward, this bar 11 acting through two projections on two longitudinal bars 12 and lifting them also. The transverse bar 11 acts at the same time on a longitudinal shutter 13 carrying at its left-hand end a pawl 14. This pawl serves as a bearing for a lever 15 subjected to the action of a spring 16, Figs. 1 and 5. The lever 15 is

secured on the extension of a transverse shutter 17 which passes above the longitudinal bars 12.

When a key of the keyboard is depressed, 5 two of the bars 12 are slightly lifted as above stated and extend beyond the others. They are thus presented with their notches 12^a in front of the shutter 17, (Fig. 6). At 10 the same time the shutter 17 is pushed forward by the bar 11; the pawl 14 is withdrawn, the lever 15 has no longer a bearing and, pulled by the spring 16, causes the rotation of the shutter 17 which engages with the two bars 12 and projects them against 15 the pawls 5 (Figs. 1 and 6). This movement takes place from right to left with an upward inclination of 45° relatively to the horizontal and the bars 12 thus lifted come in engagement, below the point, with two 20 of the pawls which, in this portion of the drum, are in the position of rest. The pawl thus engaged by the bars 12 take position II (Figs. 4 and 6) that is to say the operative position.

25 The longitudinal bars 12 might quite well be lifted to the required height directly by the action of the finger on the key for reaching the two pawls 5 of the drum 4, but the effort to be exerted would be too great and 30 the keyboard would become too stiff. The longitudinal shutter 13, pawl 14, lever 15 and its spring 16 as well as the transverse shutter 17 serve therefore only to ease the 35 keys of the keyboard and to render the work on the keyboard less tiring.

After each depression of a key of the keyboard, the drum 4 rotates to the extent of one division for presenting a new series of pawls 5 opposite the bars 12; the two pawls 40 5 placed in operative position represent each time the letter marked on the depressed key and thus the letter is recorded on the drum and owing to the advance of the latter each 45 letter, one after the other, is recorded on the said drum up to the end of the line.

By the term advance of the drum, must be understood its rotary movement about its center. Considering this drum has no axis at the center, this movement takes place in 50 the direction of the arrow between the guide-roller 3.

The advance of the drum does not directly take place through the action of the keyboard. The keyboard first acts on the counter which registers the width of the letter depressed on the keyboard, and it is only at the beginning of its movement that this counter acts on the device determining the rotation of the drum. Therefore, if the 55 letter has not been recorded on the counter, the drum does not rotate; thus by this indirect action on the device for rotating the drum, guaranty is obtained that the cast line of type will have exactly the same length 60 as the line recorded on the counter, as no

letter can be recorded on the drum without being recorded on the counter and reversely.

The counter 18 (Figs. 1 and 6) is secured on the keyboard 19 and receives the necessary impulses for throwing it in gear from 70 the longitudinal bars 12 of the keyboard (Figs. 6 and 9). One of the two bars lifted acts each time on one of the thirteen levers 20 arranged in a box 21 secured on the keyboard. 75

In Fig. 9 only one of these thirteen levers is shown, Fig. 10 illustrates them in side view.

This lever 20, once lifted, pushes towards the left (Fig. 9) a bolt 23 holding a stop lever 22 in depressed position. The apparatus comprises thirteen levers 22 and each of them is provided with a flat spring 22^a which tends to lift it and to bring its free end in the path of a cylinder 24. This cylinder 24 is composed of thirteen discs each of which is provided on its periphery with a notch 24^a. These notches are displaced one thirteenth of the circumference, thus allowing to stop the cylinder by means of the levers 22 in thirteen different positions. The axis 25 carrying the cylinder 24 supports at the left-hand end a disc 26 of tempered steel the outer edge of which is divided in thirteen parts forming as many projections of different thicknesses. Each thickness is equal to the difference of the width of the letters placed on one of the thirteen matrices composing the matrix block (see Patent No. 1,042,285) and a fixed 100 measure which in the present case of 7 millimeters (Figs. 6 and 8).

At the other end of the axis 25 is secured a pinion 27 actuated through the medium of pinions 28 and 29 secured on the axis 30 and actuated by a pinion 32, rigid with a pulley 31. The axis 30 is arranged in a tube 30^a provided with a ball joint and held in frames 33 and 33^a so that it can be lowered on the side of the pinion 28 until the said 105 pinion gets out of gear with the pinion 27. At the moment the end of the lever 22 enters into one of the notches 24^a of the drum 24, the other end of the lever 22 presses against a shutter 34 which acts on the clutch pawl 110 35 of the mechanism of the counter, Figs. 8 and 9. This pawl 34 by rising releases a movable key 36 (Figs. 12 and 13) which enters into a notch 37 provided in a ring 35 rigidly secured on a shaft 38 and rotating 115 together with the pulley 31. This movable key 36 is arranged in a cam 39 loosely mounted on the shaft 38; by entering into the ring 37, it connects these two members together and causes the cam 39 to make one 120 revolution on its shaft 38. After a revolution of the cam 39, the movable key 36 is pushed back in the cam 39 by the pawl 35 and the cam stops. It makes only one 125 revolution for each throwing into gear and 130

stops after having controlled the movements necessary for recording a letter.

In the first phase of the rotary movement, the cam 39 pressing on the lever 40, lowers the tube 30° in which is fitted the axis 30 (Figs. 6, 7 and 14). The pinion 28 carried by this pinion is moved away from the pinion 27 and continues to idly rotate without acting on the pinion 27 and through the medium of the cylinder 24 on the lever 22. Therefore, the lever 22 can be easily pushed back in its original position by the shutter 34, it can release the cylinder 24 and be stopped again by the bolt 23 in its position of rest out of the notches of the drum 24, Fig. 9. The setting back of the lever 22 in its primitive position is effected through the medium of a lever 41 secured on the axis of the shutter 34, Fig. 8. After the cam 39 has been put in engagement, a boss 39a of the cam shown in Fig. 7 raises the lever 41, Fig. 8, which moves back the shutter 34 to its original position as well as the lever 22.

Knowing now how the counter is actuated by the keyboard, it will be easy to understand the mechanism for rotating the drum 4. The cam 39 of the counter 18 is provided on the left-hand side of its cylindrical body with a recess forming a half-circle in cross section, in which is fitted a roller 42 secured to one end of the lever 43 (Figs. 7 and 8). As soon as the cam 39 has been thrown in engagement by the action of the keyboard and begins its movements, the roller 42 moves out of the recess of the cam and the lever 43 by rocking acts through a link 44 on the clutch pawl 45 of the drum actuating apparatus secured to the right of the keyboard (Figs. 7 and 8). This apparatus is composed of a support having double uprights 46 between which is arranged a grooved pulley 47 rigidly mounted on an axis 48 and receives its movement from the shaft 58 of the machine. Outside the support 46 is rigidly mounted on the same shaft 48 a coupling ring 51 provided with notches for a movable key 49 fitted in a cam 50. The cam 50 is secured on a shaft 53 in alignment with the shaft 43 and carried by an outer support 54. On the other end of the shaft 53 is secured a worm 52 gearing with a toothed wheel 55 rigidly mounted on a shaft 54 carrying a sprocket wheel 57 (Figs. 1, 3 and 8).

When the link 44 presses on the end of the pawl 45, the opposite side rises and releases the movable key 49 fitted in the cam 50 and pushed by a spring against the coupling ring 51. This key engages with a notch of the said ring and drives the cam in the rotary movement and with it the worm 52 (Figs. 8 and 3). During this time, the movement of the cam 39 of the counter 18 terminates and the roller 42 enters again in the recess of the cam 39 and releases, through

its end coupled to the link 44, the pawl 45 which comes in the path of the movable key 49, pushes it back through its incline within the cam 50 and thus disengages the latter from the ring 51. The cam 50 stops and the ring 51 continues to rotate.

The rotation of the drum can also be obtained without the help of the keyboard or of the counter, by means of an operating lever 152 (Figs. 5 and 7) which, when it is raised, lowers the rod 44 and produces the throwing into gear.

The worm 52 by making a revolution with the cam 50 causes the pinion 55 to rotate the extent of one tooth; this rotation is transmitted through a chain 55a (Figs. 1 and 3) to a pinion 59 secured on a shaft 60 which carries on its end facing the drum 4, a pinion 61 the teeth of which engage between the screws 8 having cylindrical heads, which secure the axes 7 carrying the pawls 5.

At each revolution of the cam 50, the drum rotates to the extent of one division and thus brings another series of pawls 5 opposite the longitudinal bars 12 of the keyboard.

It will be noted that the coupling sleeve allows to rotate the drum by hand backward or forward.

On the other hand, a rocking lever 153 allows to remove the errors of composition, by setting back the last series of pawls in position of rest.

When the first series of pawls 5 placed in position, that is to say representing the beginning of the recorded line, comes to the right-hand side of the machine and begins to act on the transmission levers 62 and 63, arranged in two series in a carrier 64, secured on the support of the keyboard 19 (Figs. 6 and 3), at each rotation of the drum 4, the two pawls 5 representing any letter cause a corresponding lever of the series 62 and the corresponding lever of the series 63, to pivot and their rear ends provided with projections press on the end of intermediate levers 65 and 66 (Fig. 6). The series 62 of transmitting levers is adapted to control through the levers 66 (Fig. 3) the apparatus 67 which chooses the matrix by stopping the matrix block so that the matrix carrying the required letter should be opposite the mould; the other series 63 transmits the movement through the levers 65 to the apparatus 68 which chooses the letter on the chosen matrix by stopping the rotation of the latter when the said letter is presented opposite the opening of the mould. The apparatus 67 and 68 as well as their operation are described in Patent No. 1,195,742. The starting of the main shaft and that of the mould are also described in the said patent.

The pawls 5 are then set back in their position of rest by a shutter 69 (Figs. 1 and 6)

which is actuated by the cam 50 and a lever 70 at each advance of the drum; it moves the pawls 5 down, which thus come opposite the longitudinal bars 12 of the keyboard 5 in position of rest, ready to be put again in operative position.

The lever 70 serves also to reset the shutter 17 which is connected by a lever 71 (Fig. 5) and a link 72 to a lever 74 mounted on 10 the axis 73 of the lever 70 (Fig. 5).

The addition of the thicknesses of the letters recorded on the drum 4 is effected in the following manner:

The cam 39 of the counter 18 is provided 15 on its cylindrical portion with a groove in which is fitted a roller secured to the lever 75. The cam at each revolution imparts to this lever 75 a movement from right to left and from left to right, Fig. 6. The lever 20 75 is fitted in a rod 76 which is actuated by the lever and acts on two clamping screws 77 and 78, by means of levers 82 and 83; one of the screws 77 is fitted in a small frame 33^a and the other 78 in a member 79 secured on a socket 80 sliding on a central rod 81. The latter constitutes, as will be seen hereafter a bar for measuring the lengths of the lines.

The screws 77 and 78 are of reverse pitch; 30 consequently by causing them to rotate in the same direction one of them loosens and the other clamps the central rod 81.

The central rod 81 has a sufficient length 35 for being able to move from right to left according to a distance equal to that of the longest line and to still remain sufficiently in engagement, on the right-hand side in the parts which guide it. For that purpose, this rod is guided at the right-hand side in a tube 84 secured in the two frames 33 and 33^a and carrying at its left-hand end a support 85 which guides the member 79 (Fig. 6).

On the frame 33^a is secured the small 45 frame 33^a carrying the clamping screw 77 (Fig. 6). Between these two members is arranged a lever 86 (Fig. 14) the end of which nearest the centre, that is to say nearest the central rod 81 has a thickness greater than 50 that of the widest letter capable of being cast in the machine. This end is interposed between the small frame 33^a which is provided only with a hole for the passage of the central rod and between the socket 80 which passes through the frame 33^a. The socket 80 with the member 79 carrying the screw 78 having a left-hand thread are pushed against the lever 86 by a spring 87. The lever 86 is connected by a link 88 to a lever 89 secured on the end of an axis 90 carrying at its other end the lever 40; the first function of this lever 40, as already seen, is to act on the tube 30^a for moving the pinion 28 away from the pinion 27. By the movement 95 which is imparted to it by the cam 39 in the

first phase of its movement, it acts on the axis 90 and on the lever 89 which pushes back the lever 86 and moves it away from the central rod 81. The socket 80 then loses its bearing and under the action of the 70 spring 87 it moves towards the small frame according to a distance equal to the thickness of the sized lever 90. This socket carries externally to the frame 33^a a nut 91 placed in front of the member 79. Between this 75 nut 91 and the frame 33^a passes the disc 26 of tempered steel which, as above mentioned, carries on its circumference thirteen bosses or projections of different thicknesses, each boss or projection having seven millimeters 80 minus the thickness of a letter. Therefore, if one of these projections is interposed between the frame 33^a and the nut 91, the extent of movement of the socket is equal to the thickness of the corresponding letter. 85 At the time of the advance of the socket 80, the screw 78, is tightened on the central rod 81; the latter effects therefore the same displacement from right to left as the socket 80 and moves consequently according to a distance equal to the thickness of the letter depressed on the keyboard and recorded on the drum 4.

As the disc 26 is controlled by the longitudinal bars of the keyboard and presents 95 each time the boss corresponding to the depressed letter between the nut 91 and the frame 33^a, the central rod moves each time according to a distance equal to the value of the letters depressed on the keyboard, the sum of the displacement of the central rod exactly indicates at the end of the composed line the total length of this line. If the totality of the letters and spaces is smaller than the real length L of the line, the left-hand end of the central rod indicates the margin to be spaced and it will be explained hereafter how this indication will be used for obtaining the value of the spaces, so that all the lines may be exactly justified. 110 This operation is effected by means of a reducing device 92 described hereafter.

The rod 76, in its position of rest, holds the lever 82 of the clamping screw 77 rocked to the left, that is to say in the unloosened position in which the passage of the central rod through the small frame is possible. On the contrary, the lever 83 of the second screw 78, being pulled towards the left by the spring 93, holds the screw 78 tightened on 115 the central rod, so that the latter is connected to the socket 86 and follows the same when the said socket is realized by the lever 80 and moves towards the small frame; for permitting this movement, the control rod 76 120 is provided with a recess 76^a in which is fitted the end of the lever 83, recess in which the lever 83 can move freely towards the left.

When the cam 39 acts on the lever 75, the 125

6 latter moves towards the right and draws along the control rod 76. The rod 76 first releases the lever 82 which, under the action of its spring 94, tightens the screw 77 on the 5 central rod and holds it in the position in which it has previously been set. Then the left-hand end of the recess 76^a strikes against the end of the lever 83, causes it to rock to the right and loosens the screw 78 10 which was holding the socket 80 coupled with the central rod 81. As the movement of the rod 76 proceeds, the lever 83 abuts against the wall of the member 79; the latter is carried along with the socket 80 towards 15 the right and compresses the spring 93; at the end of the movement, the lever 86 engages between its left-hand end and the small frame and holds it in this position notwithstanding the pressure of the spring 93, 20 until the next movement. When the control rod 76 has arrived at the end of its movement to the right, it comes back to the left still under the action of the lever 75. This rod 76 first abandons the end of the lever 25 83 which, under the action of the spring 93, tightens the screw 78 which connects again the central rod 80 with the socket 81. At the end of its movement to the left, the rod 76 pushes the lever 82 and thus effects the 30 loosening of the screw 77, this allowing the central rod to move upon the next movement. As the cam 39, effects only one revolution at a time, the rod 76 stops and its two movements which have just been described are 35 subsequently repeated upon each depression of a key.

On the disc 26 a boss or projection is reserved for the spaces; the movement of the central rod against this boss or projection is 40 equivalent to the thinnest space used in the body of type to be composed. Thus each space recorded is counted for its minimum of width by the counter, and it receives the necessary supplement upon justification of 45 the line according to the margin which remains to be spaced and the number of spaces contained in the line. This supplement is automatically determined by a simple movement of a lever which is released at the end 50 of the recording of a line. The central rod is provided at its left-hand end with a finger 95 (Fig. 6) which indicates on a graduated reglet 96 the advance of the line recorded on the drum 4. When nearing the 55 end of the line, it acts on the bell 97, for warning the operator. Between this rod and the rod 98 of the reducing device 92, a greater or smaller interval remains at the end of the recording operation of a line, in- 60 terval representing the margin to be spaced, that is to say the total value to be regularly distributed on the number of spaces. Each space must therefore receive in addition to its minimum thickness a supplementary thickness; the total thickness must be trans-

mitted on the mould and must adjust its opening according to this thickness at each casting of a space. The reducing device 92 (Fig. 1) is composed of a vertical support 99 connected with the counter by means of 70 three axes 100, 100^a and 100^b (Fig. 5) and also secured on the keyboard. Through the upper part of this reducing device passes a horizontal support 101 (Fig. 6) on which slides a carriage 102 carrying another support 103 on which moves parallel to the support 99 a slide-block 104; the latter carries a rule of tempered steel 105 (Figs. 15 and 16) vertically secured. The slide-block 104 is provided at its upper part with a rack 104^a 80 with which gears a pinion 106 rigidly mounted on an axis 107 rotating freely in the support 99 and in an upright 108.

On the end of the axis 107 opposite to that carrying pinion 106 is secured a disc 85 109 provided on its periphery with stop teeth with which a stop pawl 110 comes in engagement; the disc 109 is actuated by a lever 111 provided at its end with a driving pawl 112 (Fig. 5). The lever 111 is carried by the upright 108 and it is connected by a link 113 to a space lever 114 carrying the spacing bar 115 (Fig. 2). By pressing on this bar 15, the driving pawl 112 causes the disc 109 to rotate to the extent of one tooth and the stop pawl 110 holds it in this position. This movement is transmitted by the pinion 106 to the rack of the slide-block 104 carrying the rule 105 which thus moves horizontally at each space depressed on the keyboard, by advancing towards the operation and coming opposite a tooth of a dividing lever 116 (Figs. 15 and 16) which corresponds to the number of the spaces depressed. At the second space, the rule 105 105 is placed opposite a tooth which corresponds to one half the length of the dividing lever, at the third space the rule 105 comes opposite the tooth which corresponds to one third (1/3) of the total length of the dividing lever, at the fourth space the rule 105 is placed opposite one fourth of the length and so on. Consequently, if at the end of the recording of a line, the end of dividing lever 116 is 110 pushed towards the right, it pushes in front of it the piston 117 with its extension 98 which moves towards the central rod according to a distance equal to the margin which is missing in the line and which must be filled by the spaces. If the line contains only two spaces, the rule 105 being opposite the middle tooth of the lever 116 is pushed according to one half the stroke of its end and pushes the slide 103 which carries it 115 through the same distance to the right, that is to say the totality of the margin to be spaced will be divided in two portions, one for each space. If the line contains ten spaces, the rule 105 is placed opposite the tenth tooth of the lever 116, the carriage 120 125 130

103 is pushed one tenth of the total length to be spaced, and its position exactly indicates the supplement of opening to be given to the mould for casting the ten spaces belonging to this line.

The transmission of these respective dimensions on the mould is effected in the following manner:

The slide-block 102 carrying the horizontal slide 103 being pushed to the right, the interval existing between its boss or projection 102^a and the adjusting screw 118, is reduced to the same extent; in this interval is fitted the end of a disc 119 of progressive thickness. In the position of rest, the thinnest portion of the disc 119 is placed between the boss 102^a and the screw 118, the disc 119 can just pass by rotating between these two members; but when the carriage 103 and with it the carriage 102 which carries it, have been pushed to the right and have diminished the width of this interval, the disc 119 when rotating stops when both its flanks come in contact with the screw 118 on one side and with the boss 102^a on the other side. This disc constitutes therefore a wedge applied on a circular surface which sinks down more or less according to the interval remaining free. The disc 119 is actuated by a rack 120 (Fig. 5) mounted on the support 101; this rack gears with a pinion 121 fast on the end of the shaft 122 on which the disc 119 is rigidly mounted.

At the end of the recording of each line, the operator releases a lever 123 which is held by a pawl 124 in the position indicated Fig. 5. This lever 123 holds through a projection 123^a a second lever 125 in the position illustrated, but as soon as the lever 123 is released, it allows the lever 125 pulled by a powerful spring 132 to move towards the rack 120. During this idle movement, the lever 123 connected by a link 126 to a lever 127 releases the wedge 128 which, pushed by a spring 129, moves to the right (Fig. 5). By sliding in this direction its incline pulls on a nut 130 secured on a rod 131 which passes through the wedge and is fitted in the dividing lever 116. This lever is therefore, drawn by the spring 129 towards the central rod 81 and its end comes near the piston 117 of the central rod, before the end of the lever 125 has reached the rack 120. As the dividing lever 116 by moving towards the central rod 81 has pushed the slide 103 to the right, the distance between the projection 102^a and the screw 118 is thus adjusted according to the thickness of the spaces and this before the rack has been reached by the lever 125.

The lever 125 pulled by its spring pushes the rack 120 in front of it. The rack 120 causes the pinion 121 and the disc 119 to rotate, the latter stopping as soon as it can no longer pass between the boss 102^a and the

screw 118. By the stoppage of the disc 119, the rack is also stopped; the traction of the spring 132 has for effect to hold the disc 119 between the projection 102^a and the screw 118. The movement of the rack 120, the extent of which is thus determined, is transmitted through its other end 120^a to the parts of the mould which is in this way caused to be opened to the required extent.

It is obvious that the position thus given to the mould for the first line must be changed before the second line begins to be cast, but it must be maintained during the recording of two or more lines if these lines contain only a small number of types and if the beginning of the line recorded on the drum does not arrive at the transmitting levers 62 and 63 before the recording of the second line. In fact, it sometimes happens that when composing lines of short length, two or three lines are recorded before the first line begins to act on the casting mechanism. It is therefore necessary to maintain for each line the widths of the spaces determined by the dividing apparatus until these lines are cast in their turn, and after the casting of each line, to obliterate the position which has been given for this same line and to give to the parts the required position for the next line. The result may be obtained by means of an apparatus 133 which is diagrammatically illustrated in Figs. 2 and 11. On the axis 135 of a disc 134 are freely mounted a number of arms 136. A stop lever 137 holds the first arm 136 opposite the dividing apparatus in a horizontal position. Each arm is provided with a piston 138 (Fig. 11) pushed by a spring 139, the stroke being limited by a stop screw 141. At the end of the recording of the line, after releasing the lever 125 which has pushed the rack 120 and which stops according to the margin to be spaced and according to the number of spaces contained in the line, this rack being connected to a wedge 142 pushes this wedge forward to the same extent. The slope of the wedge 142 corresponds to the slope of the disc 119. The said wedge causes the piston 138 to re-enter, the extent of this movement being equal to the width to be given to the opening of the mould for the casting of the spaces. Before the return of the rack, a brake 143 (Fig. 19) which was held by the stop lever 137 connected by a link 145 to a lever 144 is released, firmly presses on the piston 138 and holds it in the position which has been given to it by the wedge 142. The stop lever 137, when releasing the brake 143, moves out of the way and allows the first arm to descend under the action of its own weight, this arm taking the vertical position in which its piston 138 acts on the mould for adjusting its opening (position I, Fig. 2). It remains in this position as long

125 130 135 140 145 150 155 160 165 170 175 180

as the first line composed is not entirely cast. In the meanwhile, the second arm II comes, at the end of the recording of the line, behind the arm I and frequently the arm III does likewise. If, during the recording of the fourth line, the first line is cast and its casting finished, it is necessary to remove the arm I which has acted on the mould during the casting of the first line from the 10 position I and to replace it by the arm which is in the position II and belongs to the second recorded line. This change is effected by a two-arm lever 147 rotating about the axis 135. This lever 147 is illustrated in 15 Fig. 2 in position of rest. The said lever 147 is actuated by a pinion mounted on its hub which is not shown in the drawing. This pinion is actuated by the composing stick 148 which, at the end of each cast line, 20 by transporting it in the known manner in the galley, causes the pinion and lever 147 to make half a revolution in the direction of the arrow. The lever 147 carries a pawl 146, whilst the arms 136 are provided with 25 corresponding spring pins 149. These pins move through a circular groove 150 of the disc 134 (Fig. 11) and this groove is provided with an incline which causes the pin to project outside when the arm 136 is in 30 position II. Consequently, when the lever 147 makes half a revolution, the pawl 146 placed behind the pin 149 of the arm 136, occupying the position I, draws along the latter up to the position of the finger 147, 35 from where it falls by its own weight and comes behind the arm horizontally arranged. The pin 149 of the arm occupying the position II is engaged by the finger 147, and pushed in the position I; then the finger 40 147 comes back to its initial position of rest. The other end of the lever 147, provided with the pawl 146, comes behind the pin 149 of the arm which is now in the position I and remains in this position until the 45 second line is cast and sent in the galley 151 and so on.

From the foregoing, it will be easily seen that the value of the spaces can be recorded for several lines without otherwise troubling about the same, considering the setting out of each cast line determines the replacement of the arm bearing the value of the spaces for the next line.

In order to be able to compose several 55 types in the same line, the counter 18 (Fig. 1) has four cylinders 24 each belonging to a different type. One or the other of these cylinders can be placed at will in the working position and thus the thicknesses of the various types contained in the same line can be added.

The operation of the whole is the following:

By depressing a key of the keyboard 19, 60 two or more pawls 5 of the drum 4 are

placed in operative position and represent the letter on the key of the keyboard. At the same time a disc 26 of the counter 18 is stopped in its rotary movement and presents that of its bosses or projections corresponding to the thickness of the depressed letter between the frame 33^a and the movable socket 80, forming together a kind of pincers. With the socket moves at the same time the central rod 81 of the counter which 75 is connected thereto by the clamping screw 78, the extent of the movement being equal to the thickness of a letter.

At the end of this movement, the other 80 screw 77 holds the central rod 81 in this new position, whilst the movable socket 80 is brought backward in the position of rest and connected again by means of the screw 78 with the central rod 81. This operation is repeated for each letter depressed on the 85 keyboard and the total advance of the central rod represents the length of the recorded line, or in other words the totality of the thicknesses of the letters contained in 90 the recorded line.

At each operation, the counter acts on the coupling of the cam 50 and of the worm 52 which cause the drum to rotate to the extent of one division and place another series of pawls 5 opposite the bars 12 of the keyboard 19. Each series of pawls 5 having thus received a position the whole of which represents the letters of a line composed on the keyboard, these pawls move towards the transmitting levers 62 and 63 which act on the control apparatuses of the main shaft of the machine and of the mould. The bell 97 struck by the central rod 81 warns the operator that he is near the end of the line. At this moment, the operator terminates his 105 line, either by completing the last word, or by dividing it; he then releases the lever 123 which allows the end of the dividing lever 116 to move towards the central rod to the extent of the value of the margin to 110 be filled by the spaces. In this movement, the carriage 102 of the dividing device 92 is moved against the wedge-disc 119; the latter by rotating records the value of the 115 spaces. This value is transmitted by the rack 120 and the wedge 142 on the space register 133 (Fig. 2) which transmits it to the mould during all the time necessitated by the casting of the line to which these 120 spaces belong.

At the end of the recording of a line, and after having released the lever 123 and having set it back to its initial position, the operator depresses the key of the keyboard which indicates the end of the line recorded on the drum 4; this causing the cast line to start towards the galley 151. These operations are repeated for each new line; from the time the first line has begun to act 125 on the casting mechanism, a letter is cast 130

at each depression of a new key and the casting takes place at the same time as the recording.

Claims.

5 1. In a machine for casting and setting movable type, a registering drum being hollow inside turning on itself, organs carried by this drum capable of taking an active or an inactive position, a keyboard disposed in-
10 side this drum which can agitate these organs in order to place them in an operative position, means actioned by said organs to start the casting mechanism.

15 2. In a machine for casting and setting movable type, a registering drum turning on itself, pawls carried by this drum capable of taking an active and an inactive position, a keyboard which can work on these pawls in order to place them in an operative posi-
20 tion for starting the casting mechanism.

25 3. In a machine for casting and setting movable type, a registering drum turning on itself and guided exteriorly by rollers, a keyboard inside of this drum, pawls carried by the drum which can be placed in an active position or an inactive position by the keyboard, means by which these pawls action on the casting mechanism.

30 4. In a machine for setting and casting movable type, a registering drum turning on itself and guided exteriorly by rollers, a keyboard at the inside of this drum, articulated pawls carried by the drum which can be placed in an active position by the keyboard, a spring arrangement keeping said pawls in active position, means by which these pawls action on the casting mechanism.

40 5. In a machine for casting and setting movable type, a keyboard, a registering drum of the letters struck on this keyboard, means by which said drum causes each time that a letter is depressed the stopping of the matrices before the mold and the starting of the casting mechanism.

45 6. In a machine for casting and composing movable type, a keyboard, a registering drum of the letters depressed on this keyboard, a rotating disk representing the thickness of the letters, means by which the keyboard actions on this disk and means by which the counter causes the drum to rotate to the extent of one division.

55 7. In a machine for casting and setting movable type, a keyboard, a registering drum recording the letters depressed on this keyboard, a rotating disk representing the thickness of the letters, means by which the keyboard actions on this disk, means for registering the size of each depressed letter, means by which the registering means causes the drum to rotate to the extent of one division.

60 8. In a machine for casting and setting movable type, a keyboard, a drum, pawls registering the letters depressed carried by

this drum, a rotating disk, means for placing in an active position at each depression of the key certain pawls and means for action on the counter.

9. In a machine for casting and setting movable type, a keyboard, a drum, pawls registering the letters depressed carried by this drum, a counting mechanism, means for placing in an active position at each depression of a key certain pawls, means for action on the counter and means by which the counter advances the drum.

10. In a machine for casting and setting movable type, a keyboard, a drum registering the depressed letters, a counting mechanism, means by which the keyboard actions this counter, means by which the thickness of the depressed letter is indicated on the counter and a device measuring this thickness.

11. In a machine for casting and setting movable type, a keyboard, a drum registering the depressed letters, a counting mechanism, a rotating cylinder forming part of this mechanism, means for stopping this cylinder at each depression, an embossed disk the thickness of which corresponds to the width of the letters, a measuring rod advancing against the projections and adjusting by its successive advancement the thickness of the letters of the line.

12. In a machine for setting and casting movable type, a keyboard, a drum registering the depressed letters, a counting mechanism, a rotating cylinder forming a part of this mechanism, means for stopping this cylinder at each depression, a disk having projections, the thickness of which corresponds to the width of the letters, a measuring rod and means for advancing this rod against the projections.

13. In a machine for casting and setting movable type, a rotating registering drum, a keyboard, a counter having a plurality of rotating cylinders, means for stopping these cylinders, a disk corresponding to each of the above cylinders and having projections, the thickness of which correspond with the width of the letters, a measuring rod and means for advancing this rod against the projection.

14. In a machine for casting and setting movable type, a rotating registering drum, a keyboard, a counter having a plurality of rotating cylinders, a series of levers and engaging in the end of each cylinder stepped projections for this lever commanded by the keyboard, a disk corresponding with each of the above cylinders and having projections, the thickness of which correspond with the width of the letters, a measuring rod and means for advancing this rod against the projections.

15. In a machine for casting and setting movable type, a keyboard, a drum registering the depressed letters, a counting mech-

- anism, means for actioning this counter by the keyboard, means forming part of this counter for indicating at once the thickness of the depressed letter, a measuring rod registering this thickness, a device for regulating the exact advancement and the stopping of this measuring rod with each letter.
16. In a machine for registering and setting movable type, a keyboard, a drum registering the depressed letters, a counting mechanism, a rotating cylinder forming part of this mechanism, means for stopping this cylinder at each depression, a disk having projections, the thickness of which corresponds with the width of the letters, a measuring rod advancing against these projections and a system of screws engaging or setting free said rod, a cam for commanding these screws.
17. In a machine for casting and setting movable type, a keyboard, a drum registering the depressed letters, a counting mechanism, a rotating cylinder forming part of this mechanism, means for stopping this cylinder at each depression, a disk having projections, the thickness of which corresponds with the width of the letters, a measuring rod advancing against these projections and a system of screws engaging or setting free said measuring rod, a cam for commanding these screws, a socket sliding over this rod, pressure means functioning alternately.
18. In a machine for casting and setting movable type, a keyboard, a drum registering the depressed letters, a counting mechanism, a rotating cylinder forming part of this mechanism, means for stopping this cylinder at each depression, a disk having projections, the thickness of which corresponds with the width of the letters, a measuring rod advancing against these projections and a system of screws immobilizing or setting free this measuring rod, a cam for commanding these screws, a socket sliding over this rod, two pressure screws commanded automatically by means started by the keyboard.
19. In a machine for casting and setting movable type, a keyboard, a drum registering the letters depressed on the keyboard, a counting mechanism actioned by the keyboard, means for measuring the thickness of the letters, a dividing system regulating the mold for the spaces, a dividing lever having stepped projections, a rule actuated by the lever acting on the opening members of the mold.
20. In a machine for casting and setting movable type, a keyboard, a drum for recording the letters depressed on the keyboard, a counting mechanism actuated by the keyboard, means for measuring the thickness of the letters, a dividing system automatically determining the thickness of the spaces, means for opening the mould to a corresponding extent.
21. In a machine for casting and setting movable type, a keyboard, a drum for recording the letters depressed on the keyboard, a counting mechanism actuated by the keyboard, means for measuring the thickness of the letters, a dividing system adjusting the mould for the spaces, a dividing lever carrying stepped projections, a rule actuated by this lever and acting on the opening members of the mould.
22. In a machine for casting and setting movable type, a keyboard, a drum for recording the letters depressed on the keyboard, a counting mechanism actuated by the keyboard, means for measuring the thickness of the letters, a dividing system adjusting the mould for the spaces, a dividing lever carrying stepped projections, a rule actuated by this lever, a carriage, a fixed abutment, a wedge-disc fitting between the preceding members for determining the opening of the mould.
23. In a machine for casting and setting movable type, a keyboard, a drum for recording the letters depressed on the keyboard, a counting mechanism actuated by the keyboard, means for measuring the thickness of the letters, a dividing system, a device recording the spaces for several lines.
24. In a machine for casting and setting movable type, a keyboard, a drum for recording the letters depressed on the keyboard, a counting mechanism actuated by the keyboard, means for measuring the thickness of the letters, a dividing system, a device recording the spaces for several lines, and comprising a disc, rotary arms and pistons on these arms for acting on the mould.
25. In a machine for casting and setting movable type, a keyboard, a drum registering the letters depressed on this keyboard, a counting mechanism actioned by the keyboard, means for measuring the thickness of the letters, a dividing system regulating automatically the width of the spaces, a dividing lever having stepped projections, a rule actuated by this lever, a carriage, a fixed abutment, a wedged disk engaging between the preceding members for determining the size of the spaces.
26. In a machine for casting and setting movable type, a keyboard, a drum registering the letters depressed on this keyboard, a counting mechanism, actioned by this keyboard, means for measuring the thickness of the letters, a dividing system, a registering device of the spaces for several lines.
27. In a machine for casting and setting movable type, a keyboard, a drum registering the letters depressed on this keyboard, a counting mechanism actioned by the keyboard, means for measuring the thickness of the spaces, a device for opening the mould to a corresponding extent.

the letters, a dividing system, a registering device of the spaces for several lines having a disk, rotative arms, pistons on these arms for acting on the mold.

- 5 28. In a machine for casting and setting movable type, a keyboard, a drum registering the letters depressed on the keyboard, a counting mechanism actuated by the keyboard, means for measuring the thickness of
10 the letters, a dividing system, a registering

device for the spaces of several lines having a disk, rotative arms, pistons on these arms for acting on the mold, means for substituting these arms one for another.

The foregoing specification of my process 15 and devices for recording a set up line on a machine for casting and setting movable type signed by me this 2nd day of May 1923.

FRANZ SCHIMMEL.

the letters, a dividing system, a registering device of the spaces for several lines having a disk, rotative arms, pistons on these arms for acting on the mold.

- 5 28. In a machine for casting and setting movable type, a keyboard, a drum registering the letters depressed on the keyboard, a counting mechanism actuated by the keyboard, means for measuring the thickness of
10 the letters, a dividing system, a registering

device for the spaces of several lines having a disk, rotative arms, pistons on these arms for acting on the mold, means for substituting these arms one for another.

The foregoing specification of my process 15 and devices for recording a set up line on a machine for casting and setting movable type signed by me this 2nd day of May 1923.

FRANZ SCHIMMEL.

Certificate of Correction.

It is hereby certified that Letters Patent No. 1,553,190, granted September 8, 1925, upon the application of Franz Schimmel, of Tournon, France, for an improvement in "Processes and Devices for Recording Set-Up Lines of Machines for Casting and Setting Movable Type," were erroneously issued to the inventor, said "Schimmel," as owner of said invention, whereas said Letters Patent should have been issued to *Societe d'Exploitation des Brevets F. Schimmel, of Nancy, France*, as the assignee of the *entire interest* in said invention as shown by the records of assignments in this office; and that the said Letters Patent should be read with this correction therein that the same may conform to the record of the case in the Patent Office.

Signed and sealed this 15th day of December, A. D. 1925.
